Attorneys.

United States Patent Office.

GEORGE B. OWEN, OF WINSTED, CONNECTICUT.

Design No. 3,520, dated June 1, 1869.

DESIGN FOR A CLOCK-CASE.

The Schedule referred to in these Letters Patent and making part of the same.

To all whom it may concern:

Be it known that I, GEORGE B. OWEN, of Winsted, in the county of Litchfield, and State of Connecticut, have invented a new and improved Design for a Clock-Case; and I do hereby declare that the following is a full, clear, and exact description thereof, which will enable others skilled in the art to make and use the same, reference being had to the accompanying drawing, forming part of this specification.

The figure is a front view of a clock, illustrating my improved design.

My invention has for its object to furnish an improved design for a clock-case, which shall be neat, simple, tasteful, and ornamental; and

It consists in the design for a clock-case herein shown and described.

A is the base of the case, the front and end upper corners of which are rounded off, as shown in the figure.

B are the sides of the case, the front edges of which are rounded off as shown.

The upper part or arch of the case is formed in four

equal sections C, meeting each other and the sides B at equal angles, as shown in the figure.

D is the door-frame, the upper part of which is formed of four equal sections d^1 , meeting each other and the sides d^2 at equal angles, and corresponding with the form of the upper part, or arch O of the case, as shown in the figure.

The door is divided into two parts by the cross-bar d^3 , so that the upper portion may receive a glass, to allow the clock-face to be seen, and the lower portion may receive a looking-glass or picture, as may be desired.

Having thus described my invention,

What I claim as new, and desire to secure by Letters Patent, is—

The design for a clock-case herein set forth.

The above specification of my invention signed by me, this 7th day of May, 1869.

GEO. B. OWEN.
